UNITED STATES PATENT OFFICE.

EDWARD F. MOHATT AND LEO C. MOHATT, OF GREEN RIVER, WYOMING.

INTERNAL-COMBUSTION ENGINE.

Application filed May 8, 1928. Serial No. 276,173.

The present invention relates to an internal combustion engine and has for its prime object to provide an engine of the multi-cylinder type, preferably of the eight cylinder type 5 with the cylinders divided into two equal series, the series being oppositely disposed.

Another very important object of the invention resides in the provision of an internal combustion engine of this nature with a crank 10 shaft structure including an outer and inner portion and means for rocking the portion.

Another very important object of the invention resides in the provision of a mechanism in conjunction with an internal combustion engine of this type for taking off the power therefrom.

A still further very important object of the invention resides in the provision of an 20 internal combustion engine of this nature which is comparatively simple in its construction, compact in its arrangement of parts, strong and durable, powerful, economical, thoroughly efficient and reliable in its 25 operation, and otherwise well adapted to the purpose for which it is designed.

With the above and numerous other objects in view as will appear as the description proceeds, the invention resides in certain novel 30 features of construction, and in the combination and arrangement of parts as will be hereinafter more fully described and claimed.

In the drawings:

Figure 1 is a top plan view of an engine 35 embodying the features of our invention,

Figure 2 is a side elevation thereof,

Figure 3 is an end elevation thereof,

Figure 4 is a horizontal longitudinal section therethrough,

Figure 5 is a longitudinal vertical section therethrough,

Figure 6 is a vertical transverse section taken substantially on the line 6—6 of Figure 5,

Figure 7 is a perspective view of the inner crank shaft, and

Figure 8 is a perspective view of the outer crank shaft.

Referring to the drawing in detail it will be 50 seen that the engine block B comprises, in the present illustration eight cylinders 5 disposed in series, one series being opposite the other so that there are always two opposed cylinders connected together and having their 55 lower portions at the center provided with longitudinally extending slots 6. A crank

casing 7 is disposed under the block and has journaled therein an outer hollow crank shaft 8 and an inner crank shaft 9. Cranks 10 project from the outer crank shaft 8 and 60 cranks 11 project from the inner crank shaft 9 through slots 12 in the outer crank shaft 8.

Pistons 14 are reciprocable in the cylinders and the pistons of two cylinders which are connected together in opposed relationship 65 are connected by a single connecting rod 15 with which one of the cranks 10, 11, is pivotally connected as at 16, the crank 10 connected to one pair, and crank 11 being connected with the rod of the adjacent pair of cylinders. 70 The connecting rod 15 is formed in pivotal sections as is indicated to advantage in Figure 5, the sections being pivoted together also at 16.

The cranks 10 and 11, of course, extend 75 through the slots 6. The cylinders 5 are preferably of the L-type having firing chambers 18 with valve seats 19 therein for the intake and exhaust gas and with these seats are associated valves 20 having valve stems 21 so slidable through bearings 22 and 23 on top of the cylinder block and terminating to be actuated by cam shafts 24 which are geared together as at 25.

One of the gears 25 meshes with a gear 26 85 which is operated by a lever 27 eccentrically engaged on one end of the inner crank shaft 9 to be rotated thereby. A beveled gear 28 is fixed to one end of the outer crank shaft and a beveled gear 29 is fixed to the adjacent end 90 of the inner crank shaft 9 in spaced relation to the beveled gear 28 and beveled in an opposite direction.

A stationary member 30 about the shaft 9 upwardly and downwardly extending pintles 95 31 on which are rotatable bevel gears 32 meshing with the gears 28 and 29. One of these gears 32 has a crank 34 secured thereto for taking off power from the internal combustion engine.

Spark plugs 40 extend into the firing chamber 18 and will be in circuit with a suitable distributor timed to operate the pistons in the cylinders on the usual well known four cycle principle. When the engine is thus operating 103 it will be seen that the piston reciprocates back and forth and rocks the cranks 10 and 11 to correspondingly rock the inner and outer shaft thereby rocking the beveled gears 28 and 29 in opposite directions and causing 110 the rocking of the gears 32 and the oscillation of the take off crank 34.

Thus we do away with the usual form of the crank shaft now in common use and attain more power because of less resistance and utilize the full stroke of the piston.

5 It is thought that the construction, operation, and advantages of the invention will now be quite apparent to those skilled in this art without a more detailed description thereof. The present embodiment of the invention 10 has been disclosed in detail merely by way of example since in actual practice it attains the features of advantage enumerated as desirable in the statement of the invention and the above description.

15 It will be apparent that changes in the details of construction, and in the combination and arrangement of parts may be resorted to without departing from the spirit or scope of the invention as hereinafter claimed or sacrificing any of its advantages.

Having thus described our invention, what we claim as new is:

1. In an internal combustion engine of the class described, an engine block including a 25 plurality of cylinders arranged in pairs, the cylinders of each pair being oppositely disposed and connected together and having slots in their central portions, said cylinders having firing chambers at their outer ends, 30 valve means associated with said firing chambers, spark plugs engaged in said firing chambers, pistons slideable in the cylinders, connecting rods projecting inwardly from the pistons and pivotally connected 35 together, the pistons of one pair of cylinders working opposite to the pistons in the next adjacent pair, a pair of crank shafts one being hollow so that the other may be disposed therein, the hollow crank shaft having 40 slots, cranks connected with the crank shaft, cranks from the inner crank shafts extending through the slot of the outer crank shaft, said cranks being pivotally connected with the pivoted ends of the connecting rods.

45 2. In an internal combustion engine of the class described, an engine block including a plurality of cylinders arranged in pairs, the cylinders of each pair being oppositely disposed and connected together and having 50 slots in their central portions, said cylinders having firing chambers, at their outer ends, valve means associated with said firing chambers, spark plugs engaged in said firing chambers, pistons slideable in the cylinders, connecting rods projecting inwardly from the pistons and pivotally connected together, the pistons of one pair of cylinders working opposite to the pistons in the next adjacent pair, a pair of crank shafts one being hollow so that 55 the other may be disposed therein, the hollow crank shaft having slots, cranks connected with the crank shaft, cranks from the inner crank shafts extending through the slot of the outer crank shaft, said cranks being pivotally connected with the pivoted ends of the connecting rods.

neeting rods, means for operating the valve means from the inner crank shaft.

3. In an internal combustion engine of the class described, an engine block including a plurality of cylinders arranged in pairs, the 70 cylinders of each pair being oppositely disposed and connected together and having slots in their central portions, said cylinders having firing chambers, spark plugs engaged in said firing chambers, pistons slideable in the cylinders, connecting rods projecting inwardly from the pistons and pivotally connected together, the pistons of one pair of cylinders working opposite to the pistons in the next 75 adjacent pair, a pair of crank shafts one being hollow so that the other may be disposed therein, the hollow crank shaft having slots, cranks connected with the crank shaft, cranks from the inner crank shafts extending through the slot of the outer crank shaft, said 80 cranks being pivotally connected with the pivoted ends of the connecting rods, means for operating the valve means from the inner crank shaft, a beveled gear on the end of the outer crank shaft, a beveled gear on the end 85 of the inner crank shaft oppositely beveled from the first mentioned gear, a stationary member having pintles extending therefrom, bevel gears rockable on the pintles and meshing with the first mentioned beveled gears. 95

4. In an internal combustion engine of the class described, an engine block including a plurality of cylinders arranged in pairs, the cylinders of each pair being oppositely disposed and connected together and having slots in their central portions, said cylinders having firing chambers, spark plugs engaged in said firing chambers, pistons slideable in the cylinders, connecting rods projecting inwardly from the pistons and pivotally connected 100 together, the pistons of one pair of cylinders working opposite to the pistons in the next adjacent pair, a pair of crank shafts one being hollow so that the other may be disposed therein, the hollow crank shaft having slots, cranks connected with the crank shaft, cranks from the inner crank shafts extending through the slot of the outer crank shaft, said cranks being pivotally connected with the pivoted ends of the connecting rods, 105 means for operating the valve means from the inner crank shaft, a beveled gear on the end of the outer crank shaft, a beveled gear on the end of the inner crank shaft oppositely beveled from the first mentioned gear, a stationary member having pintles extending therefrom, bevel gears rockable on the pintles and meshing with the first mentioned beveled gears, one of the last mentioned bevel gears 110 provided with a crank thereon to take off power from the internal combustion engine. 115

In testimony whereof we affix our signatures.

EDWARD F. MOHATT.
LEO C. MOHATT.
